UNITED STATES PATENT OFFICE.

LOUIS GRANDPRÉ, OF WOONSOCKET, RHODE ISLAND.

PULLEY-BLOCK.

SPECIFICATION forming part of Letters Patent No. 497,654, dated May 16, 1893.

Application filed January 23, 1893. Serial No. 459,365. (No model.)

To all whom it may concern:

Be it known that I, LOUIS GRANDPRÉ, a citizen of the United States, residing at Woonsocket, in the county of Providence and State 5 of Rhode Island, have invented certain new and useful Improvements in Pulley-Blocks; and I do declare the following to be a full, clear, and exact description of the invention, such as will enable others skilled in the art to which it 10 appertains to make and use the same.

This invention relates to improvements in snatch blocks or pulley blocks, and means for attaching the same and is designed more especially for outdoor use.

15 The invention has for its general object to provide a means embodying such a construction that the block will adjust itself in the direction in which the cord extends so as to lessen the wear on said cord, and a further 20 object of the invention is to provide the snatch block or casing with a shield or cover which will protect the pulley from inclement weather, and consequent rust of the parts and staining of the cord or rope.

25 Other objects and advantages will appear from the following description and claim when taken in connection with the accompanying drawings, in which—

Figure 1, is a perspective view of my improved device, illustrating the parts in an operative position. Fig. 2, is a vertical, longitudinal, sectional view of the same. Fig. 3, is a detail sectional view taken in the plane indicated by the dotted line α , α , of Fig. 2, with 35 parts broken away; and Fig. 4, is a view illustrating the position of the snatch block when the bracket plate is fixed in a horizontal position.

Referring by letter to said drawings: A, indicates the bracket plate which may be of 40 rectangular form or other suitable shape and for the sake of cheapness and durability may be of cast metal. This plate is provided with a suitable number of screw holes for the reception of securing screws as shown. This 45 plate is also provided with a central vertical slot a , and formed on the outer side of the plate and at opposite ends of said slot are lug journals b , which are designed to be placed 50 in alignment with each other, and open at the

rear into the vertical slot a . These lug journals are strengthened by flanges c , which are preferably arranged parallel to each other and at the adjacent edges of said lugs.

B, indicates a bracket. This bracket which 55 is also of metal, is of approximately T-shape in outline, having its cross branch, d , rounded at opposite ends as shown at e , so as to be allowed a horizontal swinging movement in the lug journals. The stem or arm f , of this 60 bracket terminates in a flat head g , which is provided with a central transverse aperture h , for a purpose which will be presently described.

C, indicates the snatch block or casing for 65 the pulley D, which latter may be of a construction usually employed. This snatch block which may be of cast metal is provided with the usual aperture i , for the reception of a stud or pintle to receive the pulley, and is 70 furthermore provided on its upper, longitudinal side, with a shield or cover E, which is designed to protect the interior of the block and also the pulley, as well as the hoisting rope, from moisture, and thereby prevent rusting 75 of the metal and staining of the rope. This block has its side walls extended as shown so as to form two short arms or ears k , which are provided with aligned apertures l , to receive a bolt or rivet m .

In placing my device for operation or connecting the parts, the T-shaped bracket should first be passed by the branch f , from the rear of the bracket plate through the slot a , bringing the journal ends e , into the lug journals b . 85 The snatch block should then have its ears placed over the outer end of the stem or branch f , until the apertures therein register, when the bolt or rivet m , should be tightened so as to hold the block in the position illustrated 90 in order that the shield or cover E, will always cover the pulley within the rope passing over the same.

It will be readily noted from the foregoing description, that through the medium of the 95 bolt or rivet m , the snatch block may be fixed in the position shown in Figs. 1, and 2, when the bracket plate is fixed in a vertical position, and may be fixed in the position shown in Fig. 4, when the bracket plate is fixed in a 100

horizontal position. It will also be noted that if desired the block may be loosely connected to the bracket through the medium of the bolt or rivet *m*, so as to swing in a vertical plane 5 and adapt itself to the line of draft.

In whatever position the bracket plate is placed the snatch block may be so adjusted and adjustably fixed that the cover or shield *E*, will cover and protect the interior of the 10 block and the pulley as well as the hoisting rope, which is an important desideratum.

Having described my invention, what I claim is—

The combination with the bracket plate

having the central, vertical slot and the lug 15 journals at opposite ends of said slot; of the approximately T-shaped bracket journaled in said lugs and the snatch block or pulley casting adjustably connected to one branch of the bracket and provided with the shield or cover 20 on its upper side, substantially as specified.

In testimony whereof I affix my signature in presence of two witnesses.

LOUIS GRANDPRÉ.
